(57) CLAIM

The ornamental design for a covered clothes line, as shown and described.

DESCRIPTION

FIG. 1 is an upper front perspective view of the covered clothes line.

FIG. 2 is a front elevational view thereof.

FIG. 3 is a rear elevational view thereof.

FIG. 4 is a left side elevational view thereof, the right side elevational view being a mirror image thereof.

FIG. 5 is a top plan view thereof.

FIG. 6 is a bottom plan view thereof.

FIG. 7 is a lower rear perspective view thereof.

FIG. 8 is a lower front perspective view thereof; and,

FIG. 9 is an upper rear perspective view thereof.

The broken lines in the figures are for illustrative purposes only and form no part of the claimed design.
